UNITED STATES PATENT OFFICE

149,853

DESIGN FOR A HAT BLOCKING MACHINE

William Wilson, Selma, Ala., assignor to
Wilson & Son, Selma, Ala., a firm

Application November 29, 1946, Serial No. 135,149

Term of patent 14 years

(Cl. D49—1)

To all whom it may concern:

Be it known that I, William Wilson, a citizen of the United States, residing at Selma, in the county of Dallas and State of Alabama, have invented a certain new, original, and ornamental Design for a Hat Blocking Machine, of which the following is a full, clear, and exact description, reference being had to the accompanying drawings, forming a part thereof.

In the drawing:

Figure 1 is a perspective view of a hat blocking machine, showing my new design; and

Figure 2 is a front elevation thereof.

I claim:

The ornamental design for a hat blocking machine, as shown.

WILLIAM WILSON.
